UNITED STATES PATENT OFFICE.

WILBER J. PINE, OF OSHKOSH, WISCONSIN, AND ARTHUR F. PINE, OF CASTLE ROCK, COLORADO.

VEHICLE-SPRING.

1,251,099.

Specification of Letters Patent. Patented Dec. 25, 1917.

Application filed April 23, 1917. Serial No. 164,005.

To all whom it may concern:

Be it known that we, WILBER J. PINE and ARTHUR F. PINE, citizens of the United States, residing at Oshkosh, county of Winnebago, and State of Wisconsin, and Castle Rock, county of Douglas, and State of Colorado, respectively, have invented new and useful Improvements in Vehicle-Springs, of which the following is a specification.

10 Our invention relates to improvements in vehicle springs and methods of forming the same. The objects of our invention are to provide means for constructing a vehicle spring composed of a series of flat super-
15 posed and contacting leaves, arranged in such relation to each other that the spring itself will be shock absorbing, some of the leaves acting in opposition to the others when the spring is in normal no load, (or in light load), position, but all the leaves being arranged to act in coöperation with each other to resist heavy loads, shocks or rebounds.

In this manner we are enabled to provide a spring having more than the usual number 25 of leaves (if desired), the additional number of leaves serving to strengthen the spring for heavy loads, shocks and rebounds, and also serving to increase, instead of diminishing, the flexibility of the spring when subjected to light loads. Our invention also 30 has for its object the provision of means for imparting great strength and rigidity to the central portion of the spring.

In the drawings:—

35 Figure 1 is a side elevation of a vehicle spring, embodying our invention, with dotted lines indicating the normal flexion of the upper sets of auxiliary leaves, also indicating the position which the main leaf tends 40 to assume when loaded.

Fig. 2 is a plan view of the central portion of one of the leaves.

Fig. 3 is a fragmentary view in longitudinal section, drawn to a vertical plane 45 through the central portion of the spring.

Fig. 4 is a cross sectional view, drawn to a plane through the center of the spring, and showing the clamping plates.

Fig. 5 is a similar cross sectional view, 50 showing a modified form of construction.

Like parts are identified by the same reference characters throughout the several views.

In constructing our improved spring, we preferably provide each leaf with a central 55 longitudinally extending corrugation. These corrugations may be formed so that the convex face of the corrugation will fit the concaved or depressed face of the corrugation in the next succeeding leaf, this arrangement continuing from the bottom leaf to the top one. If desired, however, we may form a portion of the leaves with corrugations bulged in one direction, and the remaining leaves with corrugations bulged in the opposite direction. For example, in Fig. 5 the corrugations of all the leaves are bulged upwardly, but in Fig. 4 the corrugation of the main leaf A and each auxiliary leaf B, B' and B'' below the main leaf are bulged 65 downwardly, as shown at C, whereas the corrugations of the upper set of leaves D, D' are bulged upwardly, as shown at C', thereby providing a central cavity which may, if desired, be filled with a core piece E. 75

In constructing our improved spring, we first form the main leaf, shaping it while hot to conform to the desired normal curvature. We then fit the auxiliary leaf B to the main leaf while such auxiliary leaf is sufficiently 80 heated so that it can be readily shaped to conform with the curvature of the main leaf, whereby the auxiliary leaf will also have the same curvature. The next auxiliary leaf B' is then fitted to the leaf B in a similar 85 manner, and each successive leaf is similarly fitted to the one preceding it in a like manner. This practice is followed as to all auxiliary leaves on convex side or below the main leaf, the work being done in accordance with long established custom. 90

After shaping the auxiliary leaves below on convex side of the main leaf to conform to the desired curvature established by the main leaf, we clamp all of these leaves together and subject the main leaf to load, the degree of load applied being substantially the normal load which the spring is designed to sustain. That is to say, we subject the spring to a weight, or tension, equivalent to 100 what might be called the normal load which the spring is designed to support as a full load. This causes the main leaf to assume an ogee curve, substantially as indicated by dotted lines in Fig. 1. We then apply the 105 auxiliary leaf D, while heated, and shape it

in conformity with the curvature of the upper surface of the main leaf, while subjected to said load. The succeeding leaf D' is then similarly applied and shaped, while heated, to the leaf D, whereby these auxiliary leaves D, D' are caused to exert normal tension toward the line of curvature of the main leaf, when loaded.

It is not essential that the auxiliary leaves B, B', etc., should be associated with, or clamped to the main leaf preparatory to the loading of the main leaf and the shaping of the auxiliary leaves D, D', etc., thereto while heated, as above explained. It will be ordinarily sufficient to merely employ the loaded main leaf to establish the desired normal curve of the leaves D and D', although, for more accurate fitting of the leaves D and D', the auxiliary leaves B, B', etc., may be assembled with the main leaf preparatory to applying the load. In this manner the auxiliary leaves, above the main leaf, have a normal curve which exactly corresponds with that of the remainder of the spring when fully assembled and loaded.

The number of auxiliary leaves used, either above or below the main leaf, is not material to this invention. But it is a fundamental feature of our invention that some of the auxiliary leaves conform in normal curvature to the normal curvature of the main leaf, while other of the auxiliary leaves conform in normal curvature to the curvature of the main leaf, when loaded. The words "normal curvature", as used in this description, are employed to designate the curvature which the leaf tends to assume when free, or substantially unloaded. We preferably locate those auxiliary leaves, whose normal curvature corresponds with the normal curve of the main leaf, below the main leaf, whereas those leaves whose normal curvature corresponds with that of the main leaf, when loaded, are preferably located above the main leaf. Clamping clips F may be employed to bind the extremities of the auxiliary leaves to the main leaf, although these are not essential. Clamping plates G and H may also be employed above and below the central portion of the spring, and may be secured to the vehicle axle by stirrup-shaped clips or yokes I, of ordinary construction. Lubricating ducts J and K may also be provided, but these are made the subject of a separate application, Serial No. 122788, filed Sept. 29, 1916, which application also shows and describes the corrugations and filler piece or core E, employed in the construction shown in Fig. 5.

We claim:

1. The method of making leaf springs, consisting, first, in forming a bow shaped main leaf and two sets of auxiliary leaves; second, shaping one set of auxiliary leaves in conformity to the normal curvature of

the main leaf when not loaded; third, shaping the other set of auxiliary leaves in conformity to the curvature of the main leaf when loaded, and fourth, assembling said auxiliary sets in position to normally act upon the main leaf in opposition to each other. 70

2. The method of making leaf springs, consisting, first, in forming a main leaf and auxiliary leaves; second, heating and assembling some of the auxiliary leaves upon one side of the main leaf and shaping them progressively upon the main leaf and upon each other successively in conformity with the normal curvature of the main leaf, and 75 third, loading the main leaf, and heating and assembling other auxiliary leaves upon the opposite side of the main leaf, and shaping them progressively upon the main leaf and upon each other successively in conformity with the curvature of the main leaf when loaded. 80

3. The method of making leaf springs, consisting in assembling two sets of auxiliary leaves upon a main leaf, with one set 90 of auxiliary leaves having a normal curvature corresponding with the curve of the main leaf when loaded, and the other set of auxiliary leaves having a normal curvature corresponding with that of the main leaf 95 when not loaded, and with the springs of each set exerting tension in the direction of the main leaf.

4. A leaf spring, comprising the combination of a main leaf and two sets of auxiliary leaves arranged with those of one set on the opposite side of the main leaf from those of the other set, all of said auxiliary leaves having normal tension in the direction of the main leaf, the leaves of one set 105 having a normal curvature corresponding with the normal curvature of the main leaf, and the leaves of the other set having a normal curvature corresponding with the curvature of the main leaf when loaded. 110

5. A leaf spring comprising the combination with a main leaf, a set of auxiliary leaves, each having a normal curvature corresponding with that of the main leaf, and another set of auxiliary leaves, each having 115 a normal curvature corresponding with the curve of the main leaf when loaded.

6. A leaf spring comprising the combination with a main leaf, a set of auxiliary leaves, each having a normal curvature corresponding with that of the main leaf, and another set of auxiliary leaves, each having a normal curvature corresponding with the curve of the main leaf when loaded, the leaves of the respective auxiliary sets being 120 arranged to exert normal tension upon the main leaf in opposite directions. 125

7. A leaf spring including the combination of two sets of leaves arranged to exert normal tension upon each other in oppo- 130

site directions, one set of leaves having a normal curvature corresponding substantially with that of the spring when unloaded, and the other set of leaves having 5 normal curvature corresponding with that of the spring when loaded, whereby the leaves of said last mentioned set may be utilized to load the leaves of the other set, when the latter are not otherwise loaded, 10 and whereby all the leaves may coöperate in supporting full loads and in resisting rebounds.
